United States Patent Office

Des. 180,876

Patented Aug. 27, 1957

180,876

PLATE OR SIMILAR ARTICLE

Takeshi Inoue, Atsuta-ku, Nagoya, Japan, assignor to Noritake Co., Inc., New York, N. Y., a corporation of New York

Application January 13, 1956, Serial No. 39,715

Term of patent 3½ years

(Cl. D44—15)

The figure is a plan view of a plate or similar article, showing my new design.

The plate is of a conventional configuration when viewed from the side and bottom thereof.

I claim:

The ornamental design for a plate or similar article, substantially as shown and described.
